UNITED STATES PATENT OFFICE.

MARK H. STRYKE, OF BROOKLYN, NEW YORK.

GARMENT.

Application filed November 12, 1926. Serial No. 147,905.

The present invention relates to garments such as women's dresses, having shoulder portions, and particularly to new and improved means attached to the inside of the shoulders of such garments for the purpose of retaining the shoulder straps of undergarments in proper relation to the shoulders of the wearer.

Heretofore, devices for this purpose have generally consisted of a piece of ribbon having near its ends the cooperating parts of snap fasteners, the cooperating faces of which are on the same side of the ribbon. Substantially one-half of said ribbon is sewed to the inside of the garment shoulder, leaving the free half of the ribbon to be passed under the shoulder straps of undergarments whereupon the part of the snap fastener thereon may then be brought into engagement with the part of the fastener carried by the half of the ribbon that is sewed to the garment. The snap fasteners used in such devices are of metal, and both the stud and the socket portion of the fastener have a metal back which is exposed and projects from the side of the ribbon opposite to the side upon which the stud and socket are located. With such devices, therefore, the metal outside of one of the parts of the fastener engages the skin of the shoulder of the wearer, so that the skin is often chafed or marred, with resulting discomfort to the wearer, particularly when the fastener is subjected to downward pressure by a heavy dress or a coat worn over the dress. Furthermore, when snap fasteners are so arranged they are difficult to open, and in fact hold the shoulder straps of undergarments so securely to the inside of the shoulder of a dress, that, if the wearer thoughtlessly attempts to remove her dress without first separating such fasteners, the holding effect of the undergarment ribbons may be so great as to tear the shoulder of the dress. As a matter of fact, the lateral pull of the shoulder straps of undergarments upon a retaining device of this kind is ordinarily quite small, and there is no need for providing any means which will strongly resist the ordinary operation of lifting a dress to remove it from the wearer's shoulders. The arrangement of the kind just mentioned does, however, hold the shoulder straps of undergarments in such a way that the pull of these straps when a dress is removed is not sufficient ordinarily to open

the snap fastener; and the opening must be done by the fingers of the wearer before she begins to remove her dress.

One of the advantages of the present invention resides in the fact that the metal back of that part of the snap fastener which is carried by the free end of the ribbon does not come into contact with the skin of the shoulder of the wearer when the device is serving its function of retaining the shoulder straps of undergarments in proper relation to the shoulder portion of a dress. Any chafing or marring of the skin is thus avoided. Another advantage of the invention resides in the fact that the cooperating parts of the snap fastener are readily separated merely by a slight pull with the fingers on the shoulder straps of the undergarments, or by the pull exerted by the dress when the shoulder of the dress is lifted prior to or during its removal. Separation of the portions of the snap fastener is thus facilitated, and any possible tearing of the dress is avoided.

The invention will be understood from the following description, taken in connection with the accompanying drawing in which Figure 1 is a plan view of the inside of the shoulder of a dress having the invention embodied therein; and Figure 2 is a perspective view of the inside of the shoulder of the dress, showing how the invention serves to retain the shoulder straps of undergarments in proper relation to the shoulder of the wearer under the shoulder portion of the dress.

Referring to the drawing, the shoulder portion of a dress is indicated at 3, the neck binding of said dress being indicated at 4, and the sleeve at 5, the seam between the shoulder and the top of the sleeve being shown at 6. In Figure 2, undergarments 8 and 9 are indicated as provided with shoulder straps 11 and 12 which are to be retained in proper relation to the shoulders of the wearer under the shoulder portion 3 of the dress.

As clearly shown in the drawing, the means for retaining the shoulder straps 11 and 12 in proper relation to the shoulder portion 3 of the dress, comprises a ribbon or tape 14 carrying near its opposite ends the parts 15 and 16 of a snap fastener, which are so attached to said ribbon that the cooperating faces of the parts of the fastener are on opposite faces of said ribbon when

the ribbon is extended in flat position. While this snap fastener may be of the well known type in which the cooperating parts are attached to the fabric by sewing, I prefer to use the well known type of snap fastener characterized by the fact that the stud and socket parts thereof are attached to a fabric by a stamping operation. With this type of snap fastener, the ends of the ribbon are folded over a short distance to give finished ends to the ribbon, and the layers of the fabric are pierced during the attaching of the stud and socket portions of the fastener both of which have metal parts which are exposed on both sides of the fabric. This is the type of snap fastener illustrated in the drawing.

As best shown in Figure 1, the ribbon 14 carrying the two parts of the snap fastener is secured near one end, as indicated by the stitching 18, to the inside of the shoulder 3 of the dress. In the drawing, the shoulder seam of the dress is shown as covered by a binding 19, and the ribbon 14 is sewed to this; but it will be understood that the ribbon 14 may be secured to the inside of the shoulder of a dress at a spot where there is no seam.

When the ribbon 14 is so attached to the shoulder of a dress, the free ends of the ribbon carrying the part 16 of the snap fastener can be looped under the shoulder straps 11 and 12 of undergarments 8 and 9 as shown in Figure 2; and the end of the ribbon carrying the part 16 of the snap fastener must be folded in upon itself, when the parts 16 and 15 of said fastener are brought into the cooperative relation shown in Figure 2.

It will be noted that when the ribbon 14 is retaining the shoulder straps 11 and 12 of the undergarments as shown in Figure 2, the metal back of the part 16 of the snap fastener is covered by the ribbon 14 and cannot touch the skin of the shoulder of the wearer. Any chafing or marring of the shoulder is thus prevented.

From Figure 2 it will be obvious that the

parts of the snap fastener are easily separated merely by lifting the shoulder of the dress adjacent the neck opening, while the shoulder straps 11 and 12 of the undergarment hold the looped portion of the ribbon 14. This easy separation of the parts of the snap fastener is due to the fact that the pull of the shoulder straps 11 and 12 on the looped portion of the ribbon 14 causes the latter to exert a force at substantially a right angle to the cooperating faces of the parts of the snap fastener. As is well known, such fasteners are easily opened when the forces tending to separate their parts are exerted in this direction, whereas such fasteners strongly resist opening when forces are exerted in directions substantially parallel to the cooperating faces of the parts of the fastener, as has been the case with the arrangements heretofore used, as explained in the first part of this specification.

What I claim is:

In combination with a garment having a shoulder portion, means attached to the inside of said shoulder portion for retaining the shoulder straps of undergarments in proper relation to the shoulder of the wearer under said shoulder portion, comprising a ribbon carrying near its opposite ends the cooperating parts of a snap fastener the cooperating faces of which parts are on the opposite faces of said ribbon when the ribbon is extended in flat position, said ribbon being sewed near one end to the inside of the shoulder of said garment with the portion of the fastener on that end exposed leaving the remainder of said ribbon free, whereby the free portion of said ribbon may be passed under the shoulder straps of undergarments and the free end of said ribbon must be folded in upon itself when the part of the fastener thereon is brought into cooperative relation with the part of the fastener on the other end of said ribbon.

In testimony whereof, I have affixed my signature to this specification.

MARK H. STRYKE.
